RUFFLING AND STITCHING MACHINE

Arthur N. Hale, Stratford, Conn., assignor to The Singer Manufacturing Company, Elizabeth, N. J., a corporation of New Jersey

Application May 25, 1944, Serial No. 537,268

17 Claims. (Cl. 112—132)

This invention relates to improvements in ruffling mechanisms for sewing machines and more particularly to ruffling mechanisms of the cam-controlled type. The primary object of the invention is to provide an improved ruffling mechanism so organized as to be adaptable to a wide variety of needs by a simple manual adjustment.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a broken-out, partially sectioned front view of a sewing machine embodying a preferred form of the invention; Fig. 2 is an enlarged view of a detail, in part sectioned on the line 2—2 of Fig. 1; Fig. 3 is an elevation of the left-hand end of the machine; Fig. 4 is a section on the line 4—4 of Fig. 1; Fig. 5 is a broken-out view, in part sectioned on the line 5—5 of Fig. 3; Figs. 6 and 7 are respectively front and rear views of the cam-follower carrier portion of the mechanism; and Fig. 8 is an elevation corresponding to the lower portion of Fig. 3 but viewed from the reverse side.

For purposes of illustration, the invention is shown applied to a zig-zag stitch sewing machine of the kind shown and described in prior Patent No. 1,020,089, dated March 12, 1912.

As illustrated herein, such machine is constructed with a frame having a bed 1 from one end of which rises a hollow standard 2 supporting a bracket arm 3 which overhangs bed 1 and terminates at its free end in a head 4. Journalled for rotation in suitable bearings provided in bracket arm 3 is a main or arm-shaft 5 carrying at one end thereof a conventional needle-bar actuating crank 6. The crank 6 is suitably connected by a link 7 to a needle-bar 8, thereby to reciprocate the needle-bar vertically in the head 4. An eye-pointed needle 9 is carried by the lower end of needle-bar 8 for vertical reciprocation therewith.

As described in the aforesaid prior patent, to which reference may be had for further details, the needle-bar 8 is vibrated laterally in the head 4. To this end, the needle-bar is journalled in a carrying frame 10 which is pivotally mounted on a stud 11 on the head 4. Connected to frame 10 by a pivot-stud 12 is a connecting rod 13, the opposite end of which embraces an eccentric 14.

arranged to be driven through suitable gearing from the main or arm-shaft 5. The eccentric 14 reciprocates the connecting rod 13 which vibrates the frame 10 about its pivot-stud 11, thereby laterally vibrating the needle-bar 8 and imparting the zig-zag motion to the endwise reciprocating needle 9.

Carried by the head 4 is a sleeve 15 in which is mounted the presser bar 16 to the lower end of which is secured the presser foot 17 which cooperates with the dog 18 in feeding the cloth through the machine. The underbed drive mechanism for the feed dog 18 and for the loop-taker, illustrated in part in dotted outline in Fig. 1, is quite unrelated to the present invention and hence need not be described.

Protruding from the rear of arm 3 are upper and lower bosses 19, 20 in which is journalled a vertically disposed cam-shaft 21. Secured to the cam-shaft 21 is a worm-wheel 22 arranged to be driven by a worm 23 secured to the main or arm shaft 5; and keyed to the lower end of cam-shaft 21 is a series of differently formed cams, four such cams being shown marked 24, 25, 26 and 27. The cams are preferably slightly separated by spacing washers and securely locked on the shaft by nut 28. In the present instance, and for reasons mentioned below, the worm-to-worm wheel ratio is such that the cam shaft 21 makes one complete revolution for each 72 revolutions of the arm shaft 5, i.e. for each 72 stitch reciprocations of the needle.

By means of a parallel link support, a cam-follower carrier generally designated 29 is suspended beneath the arm 3 and directly in front of the cams 24-27. As more particularly shown in Fig. 4, the upper, rearwardly projecting arm 30 of carrier 29 is supported by a link 31 from the elbow of a bracket 32 secured by screws 33 to the rear of arm 3. The lower, forwardly projecting arm 34 of carrier 29 is supported by a crank 35 which is secured to a rock shaft 36 journalled in the bosses 37, 38 at the lower forward edge of arm 3 (Fig. 1). By means of a tension spring 39, the ends of which are anchored in pierced lugs 40, 41 formed respectively on the lower end of bracket 32 and the top of carrier 29, the carrier is biased toward the rear of the machine; and to limit its movement in that direction, the rear end of arm 30 is formed as a stop 42 located to engage a non-metallic cushion stop 43 mounted in the lug 44 which projects laterally from the lower, cam shaft journal boss 20.

The carrier 29 supports a cam-follower 45, the inner end of which is adapted to engage one or

another of the cams 24-27. The body or stem of the cam-follower is threaded to receive a knurled adjusting wheel 46 located in the vertical slot 47 formed in the carrier 29. The cam-follower itself is located and movable in the vertical slots 48, 49 in the carrier. For the purpose of locating the cam-follower 45 in horizontal alinement with any one of the cams 24-27, the walls of slot 48 are stepped, as by the part-circular enlargements 50 (Fig. 6) which are alined with the several cams and are dimensioned to receive the reduced sleeve portion 51 of an adjustment stop member 52. As shown in Fig. 2, a compression spring 53, encircling the outer threaded end of cam-follower 45 is located between the underside of the head of a screw 54 in the outer end of the follower and a shoulder formed within member 52, thereby maintaining the sleeve portion 51 of member 52 in its selected opening 50. By pulling out member 52 to the dotted line position shown in Fig. 2 and thereby withdrawing the sleeve portion from its opening 50, the follower is freed for bodily vertical adjustment in slots 48, 49 to re-align the cam-follower with whatever cam it is desired to use. As will be recognized, parallel link mounting of the cam-follower carrier maintains the free end of the cam-follower square to the cam surfaces at all times.

The function of rock shaft 36 is to actuate the ruffler blade, below described; and, as will be understood, the several cams are selected to provide the desired variety of rock shaft and ruffler blade motions appropriate to the general character of the work to be performed. In the illustrated machine, the maximum and the minimum diameters of cams 24, 25 and 26 are the same, the sole difference between these cams residing in the number of teeth, or rise and fall portions, with which their peripheries are formed. As shown, cam 24 is provided with four such teeth (see Fig. 5), cam 25 with three, and cam 26 with six. Cam 27, which is of smaller maximum diameter than the other three, is provided with twelve such teeth. Thus cams 24, 25 and 26 all impart to rock shaft 36 oscillations which are of the same kind and degree but differing in frequency or number of oscillations per revolution of the cam shaft 21. Cam 27, on the other hand, imparts to the rock shaft 36 oscillations which differ both in degree and frequency from the other three, being shorter and more frequent.

It will be noted that the preferred number of cam shaft revolutions per revolution of the main or arm shaft 5, viz. 72, is an exact multiple of the numbers of the teeth formed on each of the cams, which results in an even number of stitches for each ruffler blade oscillation of rock shaft 36; also, that with the same gear ratio, cams having eight or nine or various other numbers of teeth may be substituted, as may be required.

Secured to rock shaft 36 and depending therefrom is a crank or carrier-arm 55; and pivotally mounted at the lower end of the carrier-arm, as by screw 56, is a ruffler blade 58. A light spring 59 is biased to urge the foot 57 and ruffler blade 58 downwardly into engagement with the cloth passing through the machine.

At the end opposite to that from which the ruffler blade projects, the pivotal foot 57 is engaged by the lower end of a tilting rod 60 mounted for endwise movement in guide lugs 61, 62 projecting from carrier arm 55; and at its upper end tilting rod 60 is engaged by the arm 63 of a lever pivotally mounted on the carrier arm 55. The other arm 64 of the tilting-rod lever operates be-

tween stop screws 65, 66, the degree of movement permitted being such that the ruffler blade is elevated from the machine bed when arm 64 engages screw 66, i. e. when the tilting rod 60 is fully depressed, as shown in Fig. 8. At the other limit of movement of arm 64 the tilting rod 60 is free to move upwardly under the influence of spring 59 and the ruffler blade is urged downwardly into ruffling position, as will be understood.

Pivotedly connected to the lower end of lever arm 64 is an actuating rod 67 which passes through a guide hole 68 in a bracket 69 which is clamped to sleeve 15. Also mounted on bracket 69 is a friction device adapted to retard endwise movement of the rod 67, thereby to hold said rod substantially stationary throughout so much of the movement of carrier arm 55 as is necessary to cause lever arm 64 to swing from the one to the other of its stop positions as determined by screws 65, 66. Further movement of carrier arm 55 overcomes the resistance of the friction device and bodily moves the actuating rod throughout the balance of the stroke of the carrier arm. In the form illustrated, the friction device comprises a bow spring 70, the central portion of which is perforated to provide clearance for the actuating rod 67 and is located in a slot 71 in bracket 69. The free ends of spring 70 carry opposed friction-blocks 72 and the set of the spring is such that the blocks frictionally clamp the actuating rod 67 against free longitudinal movement.

Thus, when carrier arm 55 starts to swing to the right from the position illustrated in Fig. 8, actuating rod 67 is held stationary by the friction-blocks 72. Lever arm 64, which is thereby restrained against following carrier arm 55, is caused to swing about its pivot, elevating lever arm 63, freeing tilting rod 60 for upward movement and permitting spring 59 to lower the ruffler blade into ruffling position. When lever arm 64 strikes stop screw 65 it is thereafter carried along bodily with carrier arm 55, the continued movement of the latter forcing actuating rod 67 to the right between, and overcoming the resistance of the friction-blocks 72. On the return movement of carrier arm 55 the friction-blocks 72 operate similarly to retard the return movement of actuating rod 67, causing lever arm 64 to swing back into engagement with stop screw 66 and, through lever arm 63, depressing tilting rod 60 and elevating the ruffler blade. The described construction frees the work from drag which would otherwise be imposed during the re-tracting movement of the ruffler blade.

From the foregoing description of the component elements, the operation of the entire ruffling mechanism will be readily understood. Rotating in the direction indicated by the arrow on the face of cam 24 in Fig. 5, the pre-selected cam actuates the rock shaft 36 in the manner described, resulting in a rapid inward or ruffling motion of carrier arm 55 (during which the blade 58 is depressed to firmly engage the cloth) and a gradual outward or return motion of arm 55 (during which the blade 58 is slightly elevated so as not to drag on the cloth). The rapid, inward movements of the cam follower carrier 29 are limited and cushioned by stop 43, as above indicated. At any time, the ruffler motion may be modified not only by shifting the follower 45 to aline with one of the other cams but also, in the case of each cam, by adjustment of the knurled wheel 46. By rotating such wheel, the free end of cam follower 45 can be adjusted toward and from

the cams so as to partake of more or less of the rise of the cam teeth, thereby increasing or decreasing the stroke of the ruffler blade and the size of the ruffle.

Having thus set forth the nature of the invention, what I claim herein is:

1. In a machine of the character described having a frame including an overhanging arm enclosing a main shaft, the combination therewith of a cam-shaft journaled on the arm, reduction gearing driving the cam-shaft from the main shaft, a plurality of differently formed cams mounted on the cam-shaft, a cam-follower carrier, parallel link members supporting the carrier from the arm with freedom for movement toward and from the cams, a cam-follower mounted on the carrier and adjustable to engage the periphery of any one of the cams, a rock-shaft supporting and actuated by one of said parallel link members, and a ruffler-blade actuated by said rock-shaft.

2. In a machine of the character described having a frame including an overhanging arm enclosing a main shaft, the combination therewith of a cam-shaft journaled on the arm, reduction gearing driving the cam-shaft from the main shaft, a plurality of differently formed cams mounted on the cam-shaft, a cam-follower carrier, parallel link members supporting the carrier from the arm with freedom for movement toward and from the cams, a cam-follower mounted on the carrier and adjustable to engage the periphery of any one of the cams, a ruffler-blade, and means for imparting the motion of the cam-follower to the ruffler-blade.

3. In a machine of the character described having a frame including an overhanging arm enclosing a main shaft, the combination therewith of a cam-shaft journaled on the arm, reduction gearing driving the cam-shaft from the main shaft, a plurality of differently formed cams mounted on the cam-shaft, a cam-follower supported from the arm and adjustable for engagement with the periphery of any one of said cams, a ruffler-blade, and means operatively connected to said cam-follower for actuating said ruffler-blade.

4. In a machine of the character described, the combination of a cam-shaft, a plurality of differently formed cams mounted thereon, a cam-follower carrier, parallel link members supporting the carrier adjacent the periphery of the cams with freedom for movement toward and from the same, a cam-follower supported in the carrier and adjustable therein for engagement with the periphery of any one of said cams, a rock-shaft supporting and actuated by one of said parallel link members, and a ruffler-blade actuated by said rock-shaft.

5. In a machine of the character described, the combination of a cam-shaft, a plurality of differently formed cams mounted thereon, a cam-follower carrier mounted with freedom for movement toward and from the cams, a cam-follower supported in the carrier and adjustable therein for engagement with the periphery of any one of said cams, a ruffler-blade, and means for imparting the motion of the carrier to the ruffler-blade.

6. In a machine of the character described, the combination of a cam-shaft, a plurality of differently formed cams mounted thereon, a cam-follower carrier mounted with freedom for movement toward and from the cams, stop means for limiting the movement of the carrier toward the

cams, a cam-follower supported in the carrier and adjustable relatively thereto to vary the movement imparted by the cams to the carrier, a ruffler-blade, and means responsive to the movement of the carrier operative to actuate the ruffler-blade.

7. In a machine of the character described, the combination of a cam-shaft, a plurality of differently formed cams mounted thereon, a cam-follower carrier mounted with freedom for movement toward and from the cams, stop means for limiting the movement of the carrier toward the cams, a cam-follower supported in the carrier, means for adjusting the follower for engagement with any one of the said cams, means for adjusting the follower relatively to the carrier in a direction toward and from the cams to vary the movement imparted by the cams to the carrier, a ruffler-blade, and means responsive to the movement of the carrier operative to actuate the ruffler-blade.

8. In a machine of the character described having a frame including an overhanging arm enclosing a main shaft, the combination therewith of a cam-shaft journaled on the arm, reduction gearing driving the cam-shaft from the main shaft, cam means mounted on the cam-shaft, a cam-follower carrier, parallel link members supporting the carrier from the arm with freedom for movement toward and from the cam means, a cam-follower mounted on the carrier and adjustable relatively thereto to vary the movement imparted by the cam means to the carrier, a rock-shaft supporting and actuated by one of said parallel link members, and a ruffler-blade actuated by said rock-shaft.

9. In a machine of the character described having a frame including an overhanging arm enclosing a main shaft, the combination therewith of a cam-shaft journaled on the arm, reduction gearing driving the cam-shaft from the main shaft, cam means mounted on the cam-shaft, a cam-follower carrier, parallel link members supporting the carrier from the arm with freedom for movement toward and from the cam means, a cam-follower mounted on the carrier and adjustable relatively thereto to vary the movement imparted by the cam means to the carrier, a ruffler-blade, and means for imparting the motion of the cam-follower to the ruffler-blade.

10. In a machine of the character described, the combination of a cam-shaft, cam means mounted thereon, a cam-follower carrier, parallel link members supporting the carrier adjacent the periphery of the cam means with freedom for movement toward and from the same, a cam-follower supported in the carrier and adjustable relatively thereto to vary the movement imparted by the cam means to the carrier, a rock-shaft supporting and actuated by one of said parallel link members, and a ruffler-blade actuated by said rock-shaft.

11. In a machine of the character described, the combination of a cam-shaft, cam means mounted thereon, a cam-follower carrier mounted with freedom for movement toward and from the cams, a cam-follower supported in the carrier and adjustable relatively thereto to vary the movement imparted to the carrier by the cam means, a ruffler-blade, and means for imparting the motion of the carrier to the ruffler-blade.

12. In a machine of the character described, the combination of a cam-shaft, cam means mounted thereon, a cam-follower carrier mounted with freedom for movement toward and from

the cam means, stop means for limiting the movement of the carrier toward the cam means, a cam-follower supported in the carrier and adjustable relatively thereto to vary the movement imparted by the cams to the carrier, a ruffler-blade, and means responsive to the movement of the carrier adapted to actuate the ruffler-blade.

13. In a machine of the character described having a frame including an overhanging arm enclosing a main shaft, a rock-shaft journaled on the arm, means actuated by the main shaft for oscillating the rock-shaft, a ruffler-blade carrier arm secured to the rock shaft, a ruffler-blade pivotally supported on the carrier arm, and a ruffler-blade tilting rod mounted for endwise movement on the carrier arm, the combination therewith of an actuating member for said tilting rod, spring means tending to lower the ruffler-blade, elevate the tilting rod and move said actuating member, friction means acting on said actuating member adapted to restrain the same against movement by said spring means, and means responsive to movement of the carrier arm adapted to overcome the resistance of said friction means.

14. In a machine of the character described having a frame including an overhanging arm enclosing a main shaft, a rock-shaft journaled on the arm, means actuated by the main shaft for oscillating the rock-shaft, a ruffler-blade carrier arm secured to the rock shaft, and a ruffler-blade pivotally supported on the carrier arm, the combination therewith of spring means tending to lower the ruffler-blade, friction means adapted to restrain movement of the ruffler-blade by said spring means, and means responsive to movement of the carrier arm adapted to overcome the resistance of said friction means.

15. In a machine of the character described,

the combination with a rock-shaft, a ruffler-blade carrier arm secured thereto, and a ruffler-blade pivotally supported on the carrier arm, of spring means tending to tilt the ruffler-blade about its pivotal support, friction means adapted to restrain tilting movement of the ruffler-blade by said spring means, and means responsive to movement of the rock-shaft adapted to overcome the resistance of said friction means.

16. In a machine of the character described, the combination with a rock-shaft, a ruffler-blade carrier arm secured thereto, and a ruffler-blade pivotally supported on the carrier arm, of spring means tending to tilt the ruffler-blade about its pivotal support, a member mounted on and movable relatively to the carrier arm to control the tilting movement of the ruffler-blade about its pivotal support, and friction means adapted to restrain bodily movement of said member with said carrier arm and thereby effect the aforesaid movement of said member relatively to the carrier arm.

17. In a machine of the character described, the combination with a rock-shaft, a ruffler-blade carrier arm secured thereto, and a ruffler-blade pivotally supported on the carrier arm, of spring means tending to tilt the ruffler-blade about its pivotal support, a member mounted on and movable relatively to the carrier arm to control the movement of the ruffler-blade about its pivotal support, friction means adapted to restrain bodily movement of said member with said carrier arm and thereby effect the aforesaid movement of said member relatively to the carrier arm, and means responsive to predetermined movement of the rock-shaft adapted to overcome the resistance of said friction means.

ARTHUR N. HALE.
